INVENTOR

Jacob Felbel.

UNITED STATES PATENT OFFICE.

JACOB FELBEL, OF NEW YORK, N. Y., ASSIGNOR TO YOST WRITING MACHINE COMPANY, OF ILION, NEW YORK.

TYPE-WRITING MACHINE.

SPECIFICATION forming part of Letters Patent No. 679,960, dated August 6, 1901.

Application filed June 22, 1900. Serial No. 21,132. (No model.)

To all whom it may concern:

Be it known that I, JACOB FELBEL, a citizen of the United States, and a resident of the borough of Manhattan, in the city of New York, 5 in the county of New York and State of New York, have invented certain new and useful Improvements in Type-Writing Machines, of which the following is a specification.

My invention relates to type-inking pads, 10 and more especially to the kind employed in the "Yost" type-writer. As heretofore constructed and mounted the pad of said machine is difficult or inconvenient to insert and remove and in the operation the fingers usually 15 become smeared with ink.

Certain objects of my invention are to so construct the ink-pad case and its support that the pad-case may be easily and quickly placed in position or removed and without 20 the necessity of the fingers coming in contact with the inked portions of the pad.

Other objects of the invention will herein-after appear.

My invention consists in certain features 25 of construction and combinations of devices, all as will be hereinafter more fully set forth, and particularly pointed out in the concluding claims.

In the accompanying drawings, Figure 1 is 30 a sectional side elevation of the type-ring and type-bars of a Yost writing-machine, showing my improved pad-case and its supporting-ring in working or normal position. Fig. 2 is an enlarged perspective view of one 35 of the lips by which the pad-case is locked in position. Fig. 3 is a plan of the type-bar ring and the pad-case thereon, the pad being omitted. Fig. 4 is a plan of a fragment of the type-bar ring or pad-case-supporting ring 40 and showing a seat for a locking-lip. Fig. 5 is a bottom plan view of the pad-case. Fig. 6 is a sectional elevation taken on the line X X of Fig. 3.

In the several views parts are omitted or 45 broken away more clearly to disclose the invention, and similar parts are designated by similar numerals of reference.

The jointed type-bars 1 are slotted to engage a fulcrum-ring 2, which is rigidly supported upon an annular casting 3, forming 50 part of the framework of the machine. The

bars are held in place upon said fulcrum-ring by a cap-ring 4, which is suitably supported upon the main ring 3 and may be considered as forming one part of the type-bar ring. 55 The type ends of the type-bars rest normally against a ring-shaped ink-pad 5, from which they are moved by means of key-operated rods 6 to strike a platen 7, a center type-guide 8 being arranged just below the platen and 60 supported upon a bracket 9. The pad 5 is square in cross-section and fits tightly in a ring-shaped metallic case 10, which opens inwardly and is formed, preferably, in one piece. The case 10 is supported on the ring 65 4 and is not a complete or continuous ring, but is divided at 11, and its adjoining ends are capped or closed, as at 12. The construction just described is found in the Yost type-writing machine. 70

I have provided upon the under side of the pad-case, preferably at its forward portion, a pair of outwardly-turned depending hooks 13, which are about equally distant from the break or division 11 and from each other. 75 Upon the supporting cap-ring 4 is provided a pair of lips 14, with which said hooks engage and by which the front portion of the pad-case is held firmly down upon the ring 4. Said lips 14 are preferably in the form of 80 small plates which fit in crescent-shaped depressions 15, formed in the upper surface of the ring 4, and are secured by screws 16, which engage threaded holes in said ring. The ends of the case are preferably held in place by an 85 overhanging bracket comprising a horizontal elevated plate 18 and vertical supporting ears 19, the latter being secured by screws 20 to the ring 4. There is just enough space between the top of the ring 4 and the under surface of the overhanging plate 18 to admit the pad-case, and hence the ends of the latter are prevented from rising and are maintained in the same plane or in their proper working positions. The pad-case ends are provided 90 with outwardly-extending curved or double-wedged lugs or bearers 21, which engage the inner vertical faces of the ears 19 and aid in positioning the case. When the latter is out of the machine, its ends spring apart, so that 100 the diameter of the case is somewhat enlarged and the ends are slightly separated,

as shown at Fig. 5; but when said case is in position the diameter thereof is contracted by the coöperation of the hooks 13, lips 14, bearers 21, and ears 19, so that the ends meet, as shown at Figs. 3 and 6.

The annular pad-case may be detached by rotating it in either direction sufficiently to disengage the hooks 13 from the lips 14, said rotary movement being conveniently effected 10 by means of short spoke-like handles 22, projecting from forward portions of the pad-case. The case may then be withdrawn from the machine, the type-bars being first bunched together in the usual manner.

15 When replacing the pad-case in position or inserting a new pad-case, it is laid or brought upon the type-ring 4 in a manner somewhat similar to the present Yost case and with the hooks 13 extending down alongside the lips 20 14 and so that the ends of the case lie just under one end of the plate 18, which latter is flared upwardly or formed with inclined wings 23 to facilitate the insertion of said case ends and force the latter down to proper position.

25 The cap-ring 4 is provided with an annular recess or cut-away at 24 of such diameter that the hooks may pass freely or loosely down alongside of the lips 14. By means of the handles 22 the case is given a slight rotation to

30 bring the ends under the middle of the plate 18. During this rotation the side edges of the hooks 13 work inwardly upon the beveled edges 25 of the lips 14, thus springing these portions of the case inwardly, and at the same

35 time the sloping cam-like edges of the bearers 21 coöperate with the vertical ears or plates 19 to crowd the meeting ends of the pad-case also inwardly, so that the said ends are brought together and the diameter of the pad-case as

40 a whole is contracted, as shown at Fig. 3, and the case is locked firmly in position upon the type ring or support. The beveled edges 25 of the lips are undercut or beveled at 26, so that in case the hooks 13 should stand a trifle

45 above their normal positions when the case has been brought to a position loosely upon the type-ring they may engage the bevel 26 and be thereby forced downwardly as well as inwardly during the rotation of the case, so 50 that they may properly engage the middle portions of the lips.

It will be observed that I have provided a curved support 4 and a curved pad-case 10, in combination with locking means, the whole 55 being so constructed and arranged that the pad-case may be placed loosely upon the support and by a slight rotation locked thereon, the locking means operating automatically when the case is rotated. By the use of the 60 handles all liability of soiling the fingers is avoided.

The lips and hooks may be of any desired length and width.

The pad-case may be made and sold as a 65 separate article of manufacture.

Variations may be made in the details of

construction, and some parts may be used without others, as indicated by the claims.

While I have shown my improvements as applied to a Yost machine, it will be understood that they may be applied also to pad-machines of other design.

What I claim as new, and desire to secure by Letters Patent, is—

1. In a type-writing machine, the combination with a curved support, of a curved rotatable pad-case, and catching devices on said support and case, said parts being so constructed and arranged that the pad-case may be placed loosely upon the support and by a slight rotation thereon cause a locking engagement between the members of said catching devices.

2. In a type-writing machine, the combination with a support, of a rotatable pad-case 85 made in ring form, handles thereon, and locking devices, the whole being so constructed and arranged that the pad-case may be placed upon the support and by said handles given a slight rotation and locked upon said support.

3. In a type-writing machine, the combination with a support, of a rotatable pad-case made in ring form and having a division, as 11, handles 22 thereon, and locking devices, 95 the whole being so constructed and arranged that the pad-case may be placed upon the support and by a slight rotation locked thereon and simultaneously contracted in diameter.

4. In a type-writing machine, the combination with a type-ring, of lips thereon, and a pad-case arranged upon said type-ring and having depending hooks to engage said lips.

5. In a type-writing machine, the combination of ring 4 having lips 14, overhanging bracket 18, 19, and divided annular pad-case 10 having bearers 21 and hooks 13.

6. In a type-writing machine, the combination with a curved pad-case having hooks 13, of a curved support, and lips 14 provided upon said support and having beveled portions 25 to engage said hooks.

7. In a type-writing machine, the combination with a curved pad-case having hooks 13, of a curved support, and lips 14 provided upon said support and having beveled portions 25 to engage said hooks, said beveled portions 25 being undercut at 26.

8. In a type-writing machine, the combination with a curved rotatable pad-case and a support, of a handle 22 arranged thereon, and means operating automatically when said case is rotated by said handle for locking said pad-case upon the support.

9. In a type-writing machine, the combination with a support, of a ring-like divided rotatable pad-case, handles 22, and means operating automatically upon rotating the pad-case by means of said handles for contracting the diameter of the pad-case and locking it in position.

10. In a type-writing machine, the combina-

tion of annular pad-case 10 having division 11, bearers 21, hooks 13, and handles 22, plate 18, inclined wings 23, uprights 19, annular support 4, and lips 14.

5 11. In a type-writing machine, the combination of annular pad-case 10 having division 11, bearers 21, hooks 13, and handles 22, plate 18, uprights 19, annular support 4, lips 14, annular recess 24 in said support 4, type-
10 bar fulcrum-ring 2, and slotted type-bars 1 pivoted upon said fulcrum-ring and confined thereon by the support 4.

12. In a type-writing machine, the combination of a type-ring having an inwardly-projecting lip 14, and an annular ink-pad case arranged to rotate upon said ring and having a rigid hook 13 adapted to engage and disengage said lip by rotative movements of the case on the ring.

15 13. In a type-writing machine, the combination of a type-ring having an inwardly-projecting lip 14 and an annular ink-pad case arranged to rotate upon said ring and having a handle 22 and a hook 13, the latter being 20 adapted to engage and disengage the lip 14 by rotative movements of said case on said ring.

14. An annular pad-case having a pair of hooks 13 projecting inwardly and downwardly 25 and adapted to inwardly-projecting lips 14 supported upon a type-writing machine.

30 15. An annular pad-case having a pair of handles 22, whereby it may be rotated, and

also having a pair of inwardly and downwardly projecting hooks 13 adapted to engage lips 14 fixed upon a type-writing machine.

16. An annular divided pad-case having a hook 13 and a bearer 21, said hook being adapted to an ear 14, and said bearer 21 being adapted to an ear 19, said lip and ear being suitably fixed upon a type-writing machine.

17. An annular divided pad-case having a pair of downwardly and inwardly extending ears 13 adapted to lips 14, and also having near its ends a pair of outwardly-projecting bearers 21 adapted to ears 19, said lips and ears being suitably supported upon a type-writing machine.

18. An annular divided pad-case having a pair of handles 22, whereby it may be rotated, a pair of ears 13 extending inwardly and downwardly from the lower portion of the pad-case and adapted to lips 14, and also having outwardly-projecting bearers 21, adapted to ears 19, said lips and ears being suitably mounted upon a type-writing machine.

Signed at borough of Manhattan, in the city of New York, in the county of New York and State of New York, this 21st day of June, 60
A. D. 1900.

JACOB FELBEL.
